I. T. SWARTZ

CARBURETOR

Filed March 1, 1920

INVENTOR.

Ira T. Swartz

BY

Benj. M. & B. Binneman

ATTORNEYS.

UNITED STATES PATENT OFFICE.

IRA T. SWARTZ, OF INDIANAPOLIS, INDIANA, ASSIGNOR, BY MESNE ASSIGNMENTS,
TO IRA T. SWARTZ, TRUSTEE, OF INDIANAPOLIS, INDIANA.

CARBURETOR.

Application filed March 1, 1920. Serial No. 362,591.

This invention relates to a carburetor for internal combustion engines, it being among the objects of this invention to produce a simple and reliable device for feeding fuel 5 to engines which will make for considerable saving in fuel, and cause the engine to run more smoothly.

In carrying the objects of my invention into effect, I provide a source of fuel, both 10 gaseous and liquid, and provide means whereby a charge of explosive mixture is ready to be drawn into the engine at all times. I am thus enabled to start an engine in the coldest weather with ease. I have 15 found that by utilizing a double source of fuel, gaseous and liquid, I obtain greater economy in operation. This invention constitutes an improvement on the invention described and claimed in my co-pending application, Serial No. 357,244, filed February 20 9, 1920, for internal combustion engines.

Referring to the accompanying drawings forming a part hereof, and in which similar reference characters denote similar parts.

25 The single figure represents a vertical section through an engine cylinder and fuel supply tank, forming the subject of this invention.

The engine cylinder 1 is supplied with a 30 water jacket 2 and carries the ordinary piston 3 and piston rod 4, intake port 5 and exhaust port 6, as are well known. Although I have here shown a single cylinder engine of the two-cycle type it is to be understood that this invention is not limited to 35 such an engine but it is applicable to the various engines of different types well known in the art.

The intake manifold 7 is connected to intake port 5 and carries a throttle valve 8 which may be actuated in any suitable manner. The fuel tank 10 has a dome or extension 11 formed thereon and communicating therewith. A pipe 12 leads from the top of dome 45 11 and is connected to manifold 7 by means of a mixing chamber 13 interposed in the path of the gaseous mixture from dome 11. I preferably include a check valve 14 in pipe 12 to prevent back fire from the engine into 50 dome 11 or tank 10.

An air intake opening 16 controlled by a spring pressed valve 17 is fixed to tank 10 and a pipe 18 leads the air to the bottom of the tank where a perforated distributor 19 uniformly distributes the air through the 55 liquid in the tank agitating the same and causing gaseous mixture to collect into dome 11. A pipe 20 leads into tank 10 terminating at point 21 near the bottom thereof. The upper end of pipe 20 is connected by 60 pipe 22 to the feed pipe 23 of the needle valve 24 of the mixing chamber 13. A stem 25 is provided to allow of regulation of the liquid fuel, and a check valve 26 prevents 65 danger of explosion from back fire.

The operation of the apparatus is as follows:

Assuming that the engine is at rest, a quantity of explosive mixture consisting of air and the lighter volatile portions of the 70 liquid fuel have collected in dome 11 and pipe 12. When the engine is started the suction thereof will draw in the explosive mixture which is present even in the coldest weather and thus the engine may be readily 75 started. When the engine has attained approximately its normal speed liquid fuel will be drawn in through needle valve 24 in addition to the gaseous explosive mixture from dome 11, thus operating the engine on a mixture of gaseous and liquid fuel. I have found that by the use of such a double apparatus I obtain greater economy of fuel in operating the engine and also obtain smoother working thereof, less danger of back fire, 80 and less liability of the engine "missing."

Having thus fully described my said invention, what I claim as new and desire to secure by Letters Patent, is:

1. A charge-forming device comprising a 90 fuel tank having a dome, a pipe leading from said dome to an internal combustion engine, means for admitting air beneath the level of the fuel in said tank, and a spray nozzle extending into said pipe from said tank the passages through said pipe and said spray nozzle being open at all times to the suction of the engine, substantially as set forth.

2. A charge-forming device comprising a 100

fuel tank having a dome, a pipe leading from said dome to an internal combustion engine, means for admitting air beneath the level of the fuel in said tank, a spray nozzle extending into said pipe, a passage leading from said tank to said spray nozzle, and check valves in the passage and the pipe said passages and said pipe being otherwise

open to the suction of the engine, substantially as set forth.

10

In witness whereof, I have hereunto set my hand at Indianapolis, Indiana, this 25th day of February, A. D., nineteen hundred and twenty.

IRA T. SWARTZ.
